Patented May 11, 1915.

UNITED STATES PATENT OFFICE.

THOMAS ALEXANDER BOYD, OF GLASGOW, SCOTLAND.

SPINNING AND TWISTING PAPER AND OTHER FIBROUS MATERIALS.

1,139,333.

Specification of Letters Patent.

Patented May 11, 1915.

Application filed April 30, 1914. Serial No. 835,515.

To all whom it may concern:

Be it known that I, THOMAS ALEXANDER BOYD, a subject of His Majesty King George, King of Great Britain and Ireland, and residing at Glasgow, Scotland, have invented 5 certain new and useful Improvements in Spinning and Twisting Paper and other Fibrous Materials, of which the following is a specification.

10 My invention relates to machines for spinning and twisting paper or other fibrous materials into yarn or twine and has for its object means for damping the said materials with water or other liquid during the 15 process of spinning or twisting and also improved means of stopping and starting the spindles of such frames in conjunction with the said damping process.

My invention consists of a delivery roller, 20 a damping roller and a trough of water or other liquid so arranged that on the delivery roller being stopped the damping roller is lifted from contact with the liquid and thus ceases to damp the paper or other 25 material being spun or twisted.

Accompanying this specification is one sheet of drawings.

My invention also includes means of stopping the spindles in conjunction with 30 the said delivery and damping rollers.

In carrying out my invention in one arrangement in which a strip of paper is drawn from a roll, damped, twisted and wound on to a bobbin, I employ a vertical 35 ring twisting spindle 1, mounted on a spindle rail 2, a tin drum 3 and a cord 4, to drive the spindle 1, all of ordinary construction. On the spindle I mount a bobbin 5, upon 40 which the twisted yarn 6 is wound by means of a ring and travelers 7 operated in the usual manner. On the framing I place a top rail 8 above and behind the spindle 1. On the top rail 8 I mount a low delivery roller 9 driven in relation to the spindle 1 in the usual manner. Above the low delivery roller 9 referred to, I mount a top delivery roller 10, which is driven by frictional contact with the former. The top delivery roller 10 has a groove 10¹ in which 45 I place a ring of india rubber or some soft substance adapted to grip and deliver the paper strip 6¹ as it is being twisted. The top delivery roller 10 is carried on a stud 11 fixed to the upper end of a bell

55 crank lever 12 which is mounted upon a shaft 13 in front of and parallel with the low delivery roller 9. The bell crank lever referred to has a horizontal limb 12¹ passing inward below the low delivery roller 9. At the inner end 12² of the said bell crank 60 lever 12 I suspend a weight 12³ which causes the top delivery roller 10 to press upon and get driven by the low delivery roller 9. The horizontal limb 12¹ of the bell crank lever 12 is lifted at its inner end 12², as hereafter described, when the top roller 10 has to be stopped. On the spindle rail 2 behind the spindle 1 I mount a tension bracket 14 with a horizontal pivot 14¹ on which I mount a cord tension lever 15 extending inward toward the tin roller 3, and having at its inner end a tension roll 16. The spindle cord 4 is passed around the spindle wherfe 1² over the tension roll 16, beneath and around the tin roller 3, and back to the 70 spindle 1. When the tension roll 16 is held at its highest point the spindle cord 4 is tightened and drives the spindle 1. When it is lowered the spindle cord 4 is slackened 75 and ceases to drive the spindle. By means of a cord grip of ordinary construction the spindle cord is gripped when it is slackened so as to insure that the spindle will stop. The cord tension lever 15 extends over a 80 short distance in front of its pivot 14¹ and carries on a T shaped adjusting screw 17, a vertical rod 18 which passes upward behind the spindle just above the top rail 8 over which a horizontal limb 18¹ on the vertical rod extends inward. On the top rail 8 I mount a catch plate 19 which engages 85 with the catch 18² on the vertical rod 18 when the latter is at its lowest point. The vertical rod 18 is kept against the said catch plate 19 by means of a spiral spring 20. 90 When the vertical rod 18 is at its lowest point and engaged in the catch plate 19 the tension lever 15 is raised to its highest point at its inner end. At the inner end 18³ of the horizontal limb 18¹ of the vertical rod 18 I fix a cross pin 21 which passes beneath the horizontal limb 12¹ of the bell crank lever 12 and which lifts the bell crank lever 12 when the vertical rod 18 is disengaged 95 and rises. On the end 18⁴ of the horizontal limb 18¹ of the vertical rod I fix a hand lever 22 standing upward to enable the worker 100 to draw the vertical rod 18 clear of its catch 105

plate 19 and thus stop the spindle 1 and raise the top delivery roller 10 clear of the low delivery roller 9.

Behind the low delivery roller 9 I mount a trough 23 in which a liquid is placed for the purpose of damping the strip of paper or other material 61. Behind and above the trough 23 I mount a horizontal shaft 24 in suitable bearings which are carried on the top rail 8. At the end of the said shaft 24 I fix a hand quadrant 25 by means of which the shaft is turned on its axis and fixed at any particular point for the purpose hereafter described. On this shaft 24 I mount loosely a dip lever 26 with a limb projecting forward over the edge of the trough. On this dip lever 26 I mount on a stud a loose roll 27 which dips into the liquid in the trough 23. On the shaft 24 carrying the dip lever 26 I fix a boss having a cross pin 29 passing under and supporting the dip lever 26 so that on the shaft 24 being operated by the quadrant 25, before referred to, one way or other the dip lever 26 is lowered into or raised partly or entirely out of the liquid. In this way the depth to which the dip roll 27 enters the liquid may be adjusted. The shaft 24 referred to carries similar dip levers for a group of spindles. By means of the quadrant 25 all the dip levers 27 mounted on the shaft are lifted clear of the liquid when the frame is stopped so as to prevent over-damping and weakening of the strip of paper or other material. It is also important when an individual spindle 1 is stopped and the top delivery roller 10 is lifted clear of the low roller 9 to lift the dip lever 26 and its roll 27 clear of the liquid so as to prevent over-damping and weakening of the strip of paper or other material when the spindle is stopped temporarily. To accomplish this I fix a cross stud 30 on the hand lever 22 before described as carried on the end 18^a of the horizontal limb 18^a of the vertical rod 18. The stud 30 referred to is below and clear of the dip lever 26. When the vertical rod 18 rises to its highest position raising the top delivery roller 10 off the low delivery roller 9, it at the same time by means of the stud 30 referred to, lifts the dip lever 26 and roll 27 clear of the water in the trough. On the catch plate 19 I pivot in a pair of vertical lugs 19^a a horizontal hand lever 31 so arranged that on its being pressed down at its front end, it carries with it the upright rod until the latter engages with its catch plate 19. The downward movement of the upright rod 18 tightens the spindle cord 4, thus driving the spindle 1 and at the same time brings the top roller 10 in contact with the low roller 9 and the dip lever 26 and dip roll 27 into the liquid. Behind and above the delivery roller 10 I mount a roll of paper 32 which is carried on a cross rod 33 in

suitable supports 34. The spindle 1 and delivery roller 10 being stopped and the dip roll 27 being clear of the liquid I draw the strip of paper or other material 61, which has to be twisted, from the roll 32 above referred to, carrying it below the dip roller 27, then over the top roller 10, downward to the twisting spindle 1 and bobbin 5. The hand starting lever 31 is then pressed down at its front end causing the spindle 1 and delivery roller 10 to start and the dip roller 27 to enter the liquid. It will thus be understood, then the whole of the spindles of the frame are stopped, by means of the shaft 24 the dip levers 27 are raised out of the trough carrying the paper strips or other material 61 clear of the liquid and also that when the spindle 1 and delivery roller 10 are stopped, at the same time, the dip lever 26 of the spindle is lifted clear of the liquid, thus preventing the paper strip or other material from getting over-damped and weakened.

Having now particularly described and ascertained the nature of my said invention, and in what manner the same is to be performed, I declare that what I claim is;

1. In a machine of the character described, a delivery roller, a damping roller over which the sliver passes, a liquid container into which said damping roller dips, a stop motion mechanism for halting the sliver feed, and means operative upon the actuation of said stop mechanism for lifting said damping roller from the liquid container.

2. In a machine of the character described, a delivery roller, a damping roller over which the sliver passes, a liquid container into which said damping roller dips, a stop motion mechanism for halting the sliver feed, and means automatically operative upon the actuation of said stop mechanism for lifting said damping roller from the liquid container.

3. In a machine of the character described, a delivery roller, a pivoted damping roller, over which the sliver passes, a stop motion mechanism comprising a drive-band tensioning roller, and means for moving the same out of tensioning position, in combination with a lever actuated thereby and engaging the pivoted damping roller to lift the same on the actuation of the stop motion mechanism.

4. In a machine of the character described, a liquid container, a damping roller dipping therein, a pivoted lever carrying said roller, an adjusting lever and means operated thereby freely engaging the damping roller lever to regulate the depth of the dip of said damping roller into the liquid container.

5. In a machine of the character described, a liquid container, a damping roller dipping therein, a pivoted lever carrying said roller, an adjusting lever and means thereon freely engaging the damping roller lever to regu-

late the depth of the dip of said damping roller into the liquid container, in combination with a stop motion mechanism comprising a lifting lever freely engaging the damping roller lever and means automatically actuating said lifting lever on the operation of the stop motion mechanism.

In testimony whereof I have signed my name to this specification, in the presence of two subscribing witnesses.

THOMAS ALEXANDER BOYD.
